UNITED STATES PATENT OFFICE.

SAMUEL F. KLOHS, OF CHICAGO, ILLINOIS.

FASTENER FOR CAR-DOORS.

1,183,833.

Specification of Letters Patent. Patented May 16, 1916.

Application filed March 28, 1910, Serial No. 551,926. Renewed October 11, 1915. Serial No. 55,353.

To all whom it may concern:

Be it known that I, SAMUEL F. KLOHS, a citizen of the United States, residing at Chicago, in the State of Illinois, have invented certain new and useful Improvements in Fasteners for Car-Doors, of which the following is a specification.

My present invention relates in general to sliding doors, and like structures, and more particularly to car side-doors; and contemplates the provision of improved means for limiting movement of the door in closing and for locking it when closed against accidental opening.

15 The principal objects of my invention are the provision of an improved construction of stop and latch for limiting the closing movement of the door and for automatically locking it in closed position as the closing movement is completed, thereby preventing accidental opening of the door and hammer-like swinging thereof back and forth upon the track with often consequent disengagement of the door from the track and loss 25 thereof.

Additional objects of my present invention are the provision of locking members which may be conveniently and inexpensively manufactured and assembled, and 30 where desired applied to doors already in use without substantial changes in such doors.

In the attainment of the foregoing objects, and certain further benefits to be below disclosed, as well as in overcoming the disadvantages referred to, I have provided the constructions disclosed in the accompanying drawings wherein—

Figure 1 is an elevational view of the side 40 of a freight car having a sliding door with my present improvements applied thereto; Fig. 2 is an enlarged plan view taken on line II—II of Fig. 1; Figs. 3 and 4 are respectively side and end elevational views of 45 an embodiment of my improved locking mechanism; Fig. 5 is an elevational view illustrative of a further embodiment of my improved locking mechanism.

Referring first more particularly to Fig. 1 50 of the drawings, it will be noted that I have here shown a customary construction including the side, 10, of a car having an opening, 11, adapted to be closed by a door 12 supported by hangers 13—13 having rollers 14—14 riding on a track 15, the door 12

being restrained from swinging outwardly from the car by the retaining bracket 16.

For the purpose of automatically locking the door 12 in closed position as it moves to the left closing the opening 11, I preferably make use of co-operating fastening and bracket members 17, and 18, one carried by the door and the other mounted for engagement therewith at a convenient point at the side 10 of the car, adjacent the forward edge of the door, the member 18 also serving the purpose of an additional restraint for preventing outward swinging of the door.

Referring now more particularly to the embodiment of my invention illustrated in Figs. 3 and 4, it will be seen that for the purpose of holding the door 12 in closed position I utilize a hook 19^a pivoted, as indicated at 30, between a pair of depending ears 31 formed on the bracket 18^a, and adapted for engagement with the teeth 24^a—24^a formed on the co-operating member 17^a carried by the door 12. To the end that the hook 19^a may be sustained in operative position, I provide a spring 32 inserted under compression in a housing 33 formed in the finger 34, by means of which said hook may be withdrawn from said teeth when it is desired to open the door. The opposite end of the spring 32 is mounted upon a stud 35 formed upon the reinforcing flange 36. As may be clearly seen on an inspection of Fig. 3, the hook 19^a, being provided with an inclined face 20^a in order that as the door moves into closed position such hook 90 may be depressed by the teeth 24^a—24^a, it offers no resistance to such closing movement but will engage such teeth and prevent any movement in the opposite direction and thus the opening of the door, until withdrawn 95 from engagement with such teeth in the manner above described.

Referring now more particularly to Fig. 5, it will be apparent that in the embodiment of my invention here shown, I mount pivotally, as indicated at 40, on the member 17^b carried by the door 12, a hook 19^b having a concave inner surface 41 for engaging with the bracket 18^b and thereby preventing opening of the door 12 save 105 when the hook is lifted out of engagement with said bracket. To the end that the hook 19^b may be caused to rise freely in the closing movement of the door as it strikes the edge 42 of the bracket 18^b, and allow such 110

movement to be effected without interference, I provide the hook with a convex surface 20^b.

Having thus described my invention and illustrated its use, what I claim as new and desire to secure by Letters Patent is the following:

1. A lock for car doors comprising a rack carried by a door adjacent the bottom edge thereof, a bracket for restraining the door from outward movement, a hook pivotally mounted to engage said rack to prevent movement of said door in one direction and automatically permitting freedom of movement of the door in the opposite direction, 10
- 15 said hook having a concaved inner surface and a convex surface, and means engageable with said concaved inner surface.
2. A lock for car doors comprising hook

and rack members carried respectively by the car and by the door adjacent the bottom edge thereof, the hook member being pivotally mounted and having a concaved inner surface, a bracket with which said surface engages to prevent opening of the door, said hook being provided further with 25 a convex surface adapted to engage the opposite edge of the bracket to allow freedom of vertical movement of the hook in the closing movement of the door.

In testimony whereof I have hereunder signed my name in the presence of the two subscribed witnesses.

SAMUEL F. KLOHS.
